Patented Apr. 30, 1918.

FIG. 2.

FIG. 1.

Inventor
Charles H. Fulson,

B. F. Ladd and Son, Inc.

Attorneys

UNITED STATES PATENT OFFICE.

CHARLES H. FULSON, OF MEMPHIS, TENNESSEE, ASSIGNOR TO BUCKEYE IRON AND BRASS WORKS, OF DAYTON, OHIO, A CORPORATION OF OHIO.

PRESSURE-REGULATING DEVICE.

1,264,173.

Specification of Letters Patent. Patented Apr. 30, 1918.

Application filed March 31, 1917. Serial No. 158,810.

To all whom it may concern:

Be it known that I, CHARLES H. FULSON, a citizen of the United States, residing at Memphis, in the county of Shelby and State 5 of Tennessee, have invented certain new and useful Improvements in Pressure-Regulating Devices, of which the following is a specification, reference being had therein to the accompanying drawing.

10 My invention relates to devices for regulating the pressure in hydrostatic presses. In particular, my device is applied to presses used for expressing oil from cotton seed and similar substances, although its application 15 is not limited to such purposes.

In such presses it is desired to move the press rapidly during its first stage of compression and more slowly during its second stage of compression, greater force being 20 exerted during the second stage to complete the operation.

In operating such presses the oil bearing meal or other substance is usually placed in bags or cloths and a number of them put in 25 the press one above the other. When the press plunger is moved a considerable portion of its travel is required to crowd the bags together. The oil does not begin to run until a pressure of about two or three 30 hundred pounds per square inch is reached. The maximum pressure desired is about 4,000 pounds per inch and if this is attained rapidly the oil will be forced out so rapidly as to destroy the cloths and permit more or 35 less fine meal to pass through the cloths in the oil. If the plunger travels so slowly as to prevent such rapid expression of the oil a great deal of the time is lost. Therefore, it is customary to move the press plunger 40 rapidly to take up the slack and then slowly as soon as the oil begins to run. It is further found at a pressure of about 3,000 pounds per inch the meal is compressed as much as possible. Any additional pressure 45 does not further compress the meal. Thus, if a pressure of 3,000 pounds is maintained for a short time nearly all the oil will be forced out, but to cause removal of all of the oil a higher pressure is desirable.

50 In order to attain the different speeds of movement above referred to it is customary to employ oil at low pressure from one accumulator and additional oil at high pressure from another accumulator. Both of

these accumulators lead to a change valve or 55 controller, the construction of which is such that the low pressure oil is first permitted to pass into the ram cylinder until a pressure of possibly 300 pounds per inch is reached therein. Then the change valve or control- 60 ler serves to shift the connections so as to cut off the low pressure oil and admit oil at high pressure from the other accumulator. The pressure in the second accumulator is about 4,000 pounds per inch. 65

The present invention provides an improved device usable in the high pressure oil line between the change valve and the press to permit the pressure to increase slowly in the ram up to a certain amount 70 and then to cause a rapid increase of the pressure. It will be understood that the device of this invention only comes into play after the slack has been taken up by the low pressure oil and when the pressure in the 75 ram cylinder has reached several hundred pounds to the inch. Then the device of this invention is applicable to cause pressure to increase slowly from that point up to about 3,000 pounds per inch and then to increase 80 rapidly from 3,000 to 4,000 pounds. This slow movement serves to cause the oil to be forced out gradually until the meal is entirely compressed. Then a rapid increase of 85 pressure does no harm to the meal and is of value in saving time.

In Figure 1 I have shown the choker member seated; and in Fig. 2 I have shown the choker member unseated. Both views are 90 vertical, longitudinal sections.

In Fig. 1, 1 is the body of the choker, 2 is the supply line from a high pressure accumulator, 3 is a cut-off member in the supply line, 4 is a plug screwed into the body 1 which has a cylindrical bore through 95 its interior carrying the spring 5 whose function is to seat the choker member 6. One end of this spring rests upon the abutment 7 and the other end against the abutment 8. The abutment 8 has orifices 9 permitting the oil to stand on both sides of it so that the pressure on both sides is equal. The abutment 8 simply provides a device against which the spring 5 may act. 100

It is to be particularly observed that the 105 member 6 is of equal diameter throughout its length on the supply side.

It will be noted that the head 10 of the

choker member has a restricted passage 11. 12 is the exit line to the press of uniform diameter throughout its length. 13 is a check valve. 14 is a continuation of the 5 exit line which leads to the press. The check valve is not essential, but convenient in effecting certain other phases of operation of the press and has nothing to do with the present invention. This is also true of the 10 cut-off 3. As shown a packing surrounding the plunger 6 is employed to prevent escape of fluid therefrom.

Method of operation.

15 The operation of the device is as follows: There is a pressure of 4,000 pounds per inch supplied from the high pressure accumulator, this entering the supply pipe 2. The liquid passes through the pipe and 20 rounds the plunger 6 and the abutment 8. It passes up through the restricted passage 11 through the tubes 12 and 14 into the exit tube. During the first part of the operation the change valve prevents passage of oil to 25 pipe 2. When the change valve is moved to cut off low pressure oil and admit high pressure oil it will be supplied from the high pressure accumulator through the pipe 2. As the oil passes through the restricted 30 passage 11 the unbalanced pressure rises until finally it exceeds the force of the spring 5. Then the plunger 6 and the head 10 of the valve move to the position of Fig. 2, thus opening wide the passage to the oil, and the 35 pressure may rapidly increase to 4,000 pounds, the pressure of the accumulator. When the meal has been pressed to extract all the oil the pressure from the accumulator is released and then the spring 5 promptly 40 forces the choker valve back to the position of Fig. 1. It will be seen that at each operation of the press the oil is permitted to move rapidly past the choker valve, thereby flushing it and cleaning out any foreign matter which 45 may have lodged in the passageway 11.

The invention depends on the unbalanced pressure on the plunger 6. It will be seen that the lower end of this plunger passes through the casing into the open air 50 and thus the oil pressure on the top of the device may tend to force it down. This is resisted by the spring 5, but as soon as the pressure of the oil is superior to the strength of the spring the choker valve opens wide 55 rapidly and remains open until the pressure drops again by the shutting off of the supply of oil. The action of the plunger 6 does not at all depend on an excess of pressure on one side of the abutment 8 over the pressure on the other side. In fact, the pressure 60 on both sides is substantially equal except for the slight drop of pressure caused by the small size of the passage 11. The oil flows readily past the abutment 8 and exerts no 65 pressure in either direction thereon.

Having thus fully described my invention, what I claim as new and desire to secure by Letters Patent, is:—

1. In a device of the character described, the combination, with a body having oil 70 passages, a choker valve seat, a valve member, resilient means to keep said valve member seated, a restricted passageway communicating with the respective oil passages on each side of said valve seat, whereby the 75 fluid flows through the restricted passage from one side of the valve to the other until the oil pressure is sufficient to overcome the valve seating means when the valve is thrown completely open and the passage of 80 the oil is unrestricted.

2. In a device of the character described, the combination, with a body having oil 85 passages and a choker valve seat, the passage at one side of the seat being smaller than at 90 the other side of the seat, a choker valve adapted to coöperate with said seat and terminating in a face corresponding with the smaller diameter of the oil passage, a spring acting to seat said choker valve, a reduced 95 passage communicating with said oil passages, whereby a reduced flow is permitted until the oil pressure overcomes the spring and the valve is thrown wide open.

3. In a device of the character described, 100 the combination, with a body having oil passages and a choker valve seat, a passage at one side of the seat, the passage on the exit side of the seat being smaller than on the inlet side, a restricted passage communicating 105 with said inlet and outlet passages through which the oil normally flows, a choker valve adapted to coöperate with said seat and terminating in a face corresponding to the smaller diameter of the exit passage, 110 and a spring acting to maintain said choker valve on its seat, whereby when the oil pressure overcomes the spring the valve is thrown wide open and the oil flows by without restriction.

4. In a device of the character described, the combination, with a body having oil 115 passages and a choker valve seat, a passage at one side of the seat, the passage on the exit side of the seat being smaller than on the inlet side, a restricted passage communicating with said 120 inlet and outlet passages through which the oil normally flows, a choker valve adapted to coöperate with said seat of the same diameter throughout its body save with a smaller 125 face corresponding with the smaller diameter of the exit oil passage, and a spring acting to maintain said choker valve on its seat, whereby when the oil pressure overcomes the spring, the valve is thrown wide open and the oil flows by without restriction.

5. In a device of the character described, the combination, with an inlet oil passage of one diameter and an outlet passage of a 130

smaller diameter, a valve seat, a valve member coöperating with said seat, said valve member having a restricted passage therein which communicates with said inlet and outlet passages and said valve member being of the same diameter throughout its length save where one end is reduced to the size of the exit passage and the other end is reduced to pass through said body, resilient means for keeping said valve member seat-

ed, means on said valve member against which one end of the spring acts to keep said valve member seated, apertures through said means whereby the spring pressure keeps said valve member seated and the oil pressure will unseat said valve member when it overcomes the spring pressure. 18

In testimony whereof, I affix my signature.

CHARLES H. FULSON.
